Invention:
Joseph Cawthon

UNITED STATES PATENT OFFICE.

JOSEPH CAWTHRA, OF ROCHESTER, NEW YORK.

CORN-HUSKER.

Specification of Letters Patent No. 18,571, dated November 10, 1857.

To all whom it may concern:

Be it known that I, JOSEPH CAWTHRA, of the city of Rochester, in the county of Monroe and State of New York, have invented a new and Improved Machine for Husking Indian Corn; and I do hereby declare that the following is a full and exact description of the same, reference being had to the accompanying drawings and to the 10 letters of reference marked thereon.

The nature of my invention consists in constructing two or more rollers to run in juxtaposition with one or more grooves in each, running laterally, and so as to meet in 15 revolving, for the purpose of clasping the ears of corn.

A fine saw or bladed wheel is provided to run at the ends of the rollers where the butt of the ear is placed which for the sake 20 of convenience is the outside in my machine. An endless belt is provided to revolve around two centers or over two rollers by which the belt is stretched along the lower part of the machinery; upon which belt the 25 corn is dropped by the grooved rollers when the butt is properly cut and carried along by the belt under a grating of coarse wire or rods running laterally with the ears of corn and while the ears are thus carried 30 along under such grating a revolving wheel called the husker with teeth projecting a sufficient distance tears up the husks from the tassel end and brings them within the sphere of another wheel called a curved 35 toothed fan which seizes the husks thus loosened and started and clears the ear entirely from husks and all its covering and the fan of the wheel cleans the ear and drives the husks and all the refuse matter 40 out of the machine; while the ear goes on upon the belt and is deposited at the end opposite from that at which it entered.

To enable others skilled in the art to make and use my invention I will proceed to 45 describe its construction and operation.

I prepare a framework of wood or iron of any convenient dimensions as represented in Figure 1 at "a". On one side I place a driving wheel "B" which by cogs meshing 50 into the cogs of "c" propels a shaft "d" running at right angles with the driving wheel a belt from a pulley affixed to the inside part of the axle of the driving wheel propels the wheel F.

55 "h" is a wheel which drives the wheel I into the extended cogs of which it meshes

and has a long axle around which as one center the belt "p" revolves. The wheel I meshes also into the wheel J and the wheels I and J are affixed to the axle of the rollers "l" and "k".

m and n are spiral or elastic spring disks (the spring being behind the disk) by which the pressure is adjusted to the different dimensions of ears.

"o" Fig. 3 is an inclined table to facilitate the feeding of the machine.

"p" represents the belt as it comes around the axle of the wheel h which last mentioned wheel the belt "p" propels. This belt is 70 plainly shown in Fig. 3 at "p" "p".

"e" is a cog wheel which propels the fan and is plainly represented in Fig. 3 at "e".

q is a mere covering to the fan which may be thrown back as in Fig. 3.

"r" represents the position of a spiral or elliptic table or platform on which the upper part of the belt passes and is kept pressed against the grating by the table or platform for the purpose of keeping the ears 80 of corn firmly and regularly in their places and compelling both large and small ears to roll over and over as they pass from rod to rod in the grating.

The table and spring are represented in 85 Fig. 2 at "r" upon the outside of the belt "p." I fasten halfrounds of wood at convenient distances apart which as they crowd by the ears of corn roll them over and pass them along from space to space between the 90 rods each halfround moving each ear the distance of one round in the grate—this rolling process loosens the husks, makes the labor lighter and forwards the ear to the place of deposit—the saw or edged wheel 95 "4" is propelled by a belt from a pulley at the end of the shaft "d."

Fig. 2 is a section cut transversely through the fan.

In Fig. 2 "1" represents the arms of the 100 fan "2" a section of the husker "r" the spring table "q" the cover of the fan cut transversely "3" the plane and opening apron and at which the husks and dirt are discharged.

105 Fig. 3 represents a section of the fan, the husker "z" "z," the belt with halfrounds, the saw or edged wheel "4" sections of the rollers "l" and "k."

Fig. 4 represents the grating, "3" "3," 110 the husker "2" "2" and a part of the belt "p."

When the driving wheel "B" is put in motion the shaft "d" and the wheel "F" are driven, the belt "p" which runs around the axle of the wheel "F" drives the wheel "h" which in its turn drives "I" and I drives J. The pulley at the end of the shaft "d" drives the saw or edged wheel "4" in Fig. 3 and the wheel "E" as seen in Fig. 3 drives the fan, and a belt from a pulley upon the inside of the axle of the fan extending to the axle of the husker drives the husker.

The teeth of the husker are made short and the husker runs with great velocity. They take up the husks from near the end of the ear and place them within reach of the fan. The fan consists of curved arms with teeth upon cross plates at the perimeter; the curved arms giving to the plates and teeth a curved form and fit them to take husks and strip the husks lengthwise of the ear and from the tip to the butt.

The fan is made to run so near the husker as to keep the husker clean, and the speed of the fan and the tattered condition of the 25 husks when taken by it, prevents any clogging in the fan. The force of the fan and the violent current of air produced throws all the husks and refuse matter out of the machine with great facility and keeps the 30 machinery at all times free and in working order.

What I claim as my invention and desire to secure by Letters Patent is—

The grooved rollers "l" "k" saw wheel 35 "4" and endless apron "p" in combination with the husker "2" grating "3" and curved toothed fan "1" the whole being constructed substantially as herein set forth.

JOSEPH CAWTHRA.
